SCABBARD

Howard M. Pierce and John H. Hermson, Brook-
lyn, N. Y., assignors to A. G. Spalding & Bros.
Inc., New York, N. Y., a corporation of Dela-
ware

Application July 1, 1938, Serial No. 216,936

5 Claims. (Cl. 280—11.38)

The present invention relates to improvements in scabbards for ice skates and a method of making the same.

Skate scabbards heretofore proposed usually consisted of a pair of side strips of leather or the like with a toe portion of greater width than the body of the side strips, and integral therewith. A base strip of narrower width than the side strips and of equal length was usually interposed between the side strips to space the same apart a proper distance to receive the runner of the skate.

Scabbards of the type described are very expensive in their production since the side strips have to be cut from leather blanks twice or more times the width of the final strips to provide for the projecting portion or pocket in which the forward end or toe of the skate is placed. Since the scabbard, if it is to fit the skate properly, and particularly the toe portion, is usually required to be of particular curved shape, a considerable amount of leather is wasted even if the blanks are laid out as economically as possible.

It is, therefore, a principal object of the present invention to provide a skate scabbard which possesses all the advantages of the proposals made heretofore but which is produced more economically.

A principal feature resulting from the attainment of this objective is a scabbard, the forward or toe portion of which is an element made separately from the main body thereof.

Another important feature of this invention is the provision of a scabbard which is adapted to envelop the runner or blade of a skate, and the side strips of which are of substantially uniform shape and size throughout their length.

Since skates of various types and shapes, depending on their particular purpose, are in common use, the skate scabbards according to previous proposals had to be made specially for each particular type.

It is therefore a vital object of the present invention to provide skate scabbards the main bodies of which are substantially alike.

A feature of this invention consists in the manufacture of side and spacing or base strips which may be used as the main body for a variety of skate scabbards suitable to fit different types of skates.

Another important object of the present invention is the provision of a toe cap or pocket which determines the shape of the forward portion of the scabbard.

55 Features of the invention for attaining the last

mentioned objective are the provision of a toe cap or pocket at one end of the main body of the scabbard; an extension of the base strip which forms a part of the main body of the scabbard for separating or spacing apart the two side portions of such a toe cap; the manner of securing the two side portions of the toe cap to the forward end of the main body so as to shape thereby the extension of the base strip in accordance with the curvature of the toe portion of a particular type of skate; and the shaping of the toe cap or pocket itself by such securing.

Other important objects of the present invention consists in the provision of a toe cap or pocket for a skate scabbard which is of such a nature that it will adapt itself to slight irregularities or differences in the shape of the forward or toe portion of the skate and which is secure against ripping apart.

It is still another object of the present invention to provide a scabbard which grips the runner of a skate securely and clings thereto tightly so as to absorb all moisture from the blade and keep the same dry when not in use.

A feature of the invention for attaining this objective is the shaping of the side strips or the spacing strip, respectively, or of both so that the inner walls of the spacing strips are inclined toward each other and thus under tension when applied to the skate blade.

Still other objects, features and advantages will be apparent from the following detailed description and the drawing, in which

Figure 1 is a side view of a scabbard according to the invention applied to one type of skate.

Fig. 2 is a perspective view of the scabbard shown in Fig. 1.

Fig. 3 is a top view of the forward part of the scabbard according to the invention.

Fig. 4 is a perspective view of the forward part of the spacing or base strip according to the invention.

Fig. 5 is a section along line 5—5 of Fig. 2.

Fig. 6 is a view similar to Fig. 4, but showing a modification of the invention.

Fig. 7 shows a blank for the forward portion or toe pocket of the scabbard according to the invention.

Fig. 8 is a fractional side view of another form of the scabbard according to the invention.

Fig. 9 is a view similar to Fig. 8, but showing the scabbard in still another form.

Before describing the present improvements and mode of operation thereof in detail it should

be understood that the invention is not limited to the details of construction and arrangement of parts shown in the accompanying drawing, which are merely illustrative of the present preferred 5 embodiments, since the invention is capable of other embodiments, and the phraseology employed is for the purpose of description and not of limitation.

The scabbard 10 according to the present invention is produced as follows:

A pair of side strips 11 of leather or similar material of substantially equal width throughout their length are inclined at their forward ends 12, as shown in Fig. 3 of the drawing. A narrow base strip 13 of greater length than side strips 11 is placed between the latter adjacent the bottom edge 14; and the side and base strips are temporarily secured together by tacking or the like so that at the rear end the side and base 15 strips are of even length, while a portion 15 of the base strip which terminates in an inclined or rounded end 16, projects beyond the forward ends 12 of the side strips. Base strip 13 may either be made of relatively flexible leather or similar material, in which event it may be substantially straight throughout its length, or if made of relatively inflexible material, the forward projecting portion 15 preferably should be slightly curved upwardly, as shown for example in Fig. 4.

In order to obtain tighter gripping of the skate blade by the side strips 11, the sides 17 of the base strip 13 may be inclined toward each other as shown in Fig. 5, or inclined longitudinally extending grooves 18 may be provided near the lower edge of the side strips 11 as shown in Fig. 6, and a base strip 13a of substantially rectangular cross-section be inserted and secured in grooves 18 to space apart the side strips 11. In such a manner, the side strips 11 are placed under considerable tension so that when a skate blade is inserted therebetween they exert a strong gripping force upon the skate blade, prevent any moisture from entering, and absorb all moisture from the blade.

According to the present invention, the toe pocket 19 of the scabbard is formed as an element separate from the side strips 11. In forming such a pocket, a blank or pattern 20 of a shape substantially similar to that shown in Fig. 7 is cut from a sheet of relatively flexible material, such as fine-grain leather, impregnated fabric, rubber composition or the like. Such blank 20 is folded about its center-line 21, placed at its base 22 tightly about the projecting portion 15 of the base strip 13 and secured at its free ends 23 to the forward ends 12 of the side strips 11.

By drawing the upper or lower edges 24, 25, respectively, of the rear ends 23 different amounts toward the rear of the scabbard, the pocket may be given different shapes. For example, Figs. 1, 8 and 9 disclose three different shapes obtainable by such a method. By comparing the pocket of Figs. 1 or 2 with that of Fig. 8, it will be seen that the rear upper edge 24 of the pocket of Fig. 1, indicated in dot-and-dash lines in Fig. 8, is drawn back a sufficient distance to curve the bottom edge 26 of the pocket, and the projecting portion 15 of the base strip likewise to a slightly larger angle relative to the bottom edge 14 of the side strips 11. For obtaining an extremely large angle of bottom edge 26 relative to edge 14, or in other words, a still smaller radius of curvature of edge 26, the forward edge 21' is preferably shortened and preshaped to the desired radius, 75 as indicated in Fig. 9. The forward portion 15

of the bottom strip may either be bent to the desired curvature, or, a preshaped strip, as shown in Fig. 4, may be used.

After the pocket 19, including the forward portion 15 of the base strip 13, has been given the desired shape, the rear ends 23 are permanently secured to side strips 11 by stitching 27, metallic fasteners 28, or the like. Thereafter the side strips 11 and the pocket 19 are stitched to the base strip 13 by a common line of stitches 27' extending from the tip 16 of the base strip to the rear end of the scabbard, and excess portions, such as the rear and upper edge portions 24 and 29 may be cut off to give the pocket its desired final shape and to improve the appearance thereof.

A scabbard as shown in the drawing may also be made and assembled in a different manner than described above. For example, the blank 20 for the toe pocket may be cut to its finally desired shape depending on the particular type of 20 skate for which it is intended and the side strips 11 may be secured by stitching 27 to the ends 23 of the blank so that they are disposed at a wide angle to each other. Thereupon, the side strips 11 are placed upon each other whereby the blank 20 is folded; the base strip 13 is then inserted between the side strips 11 and the side portions of the pocket 19; and the line of stitching 27' is formed to secure the side strips 11 and the pocket 19 to the base strip 13.

By making the two side portions of the pocket 19 integral with each other and by omitting all stitching along the front wall 33, shown particularly in Fig. 3, a certain amount of resiliency is obtained which permits the front wall 33 to assume slightly different angles when the toe portion of a skate is inserted therein. The front wall 33 therefore fits tightly about the edges of the toe portion of the skate even if such toe portion differs slightly from the normal shape 40 of the pocket 19.

Such resilient construction possesses decided advantages over relatively rigid constructions previously proposed. Since even skates of the same general type differ slightly in the particular 45 shape and angle of their toe portion, a scabbard made according to previous proposals would fit properly one specific skate for which it was "custom-made", but not any other skate of the same general type but differing from the first in minor 50 respects. However, a resilient scabbard according to the present invention will automatically adapt itself to minor differences in the toe portions of various skates of the same general type and fit the toe portions of each of such skates 55 properly.

The resilient construction of the pocket 19 and the absence of any stitching along its front wall 33 has the following further advantage over the nonresilient constructions previously proposed:

An attempt to fit the toe portion of a skate tightly and fully into a nonresilient stitched pocket, easily wedges apart the side portions thereof and tears the seam at its forward end, particularly if the toe portion of the skate differs slightly from the inner contour of such a pocket. However, when a similar attempt is made to insert the toe portion of a skate into the resilient pocket according to the present invention which possesses no stitching along its front wall 33, the latter yields to the pressure of the toe portion of the skate until the toe portion fits tightly and fully into the pocket and against the front wall 33. Therefore, because of its ability 75

to yield and adapt itself automatically to the contour of the toe portion of the skate, the pocket 19 has an increased resistance to wear and a longer life.

5 For exerting lateral yielding pressure upon the toe portion of the skate, the outer surfaces 34 of the forward ends 12 of the side strips 11 are inclined toward each other, as previously described and shown in Fig. 3, and the end portions 23 of 10 the pocket are stitched to these inclined surfaces 34 so that the side walls of the pocket are brought close to each other, particularly at 35. The inner surfaces 36 of the ends 12 of side strips 11 may also be inclined outwardly to facilitate 15 the insertion of the skate blade.

For securing the scabbard 10 according to this invention to a skate 30, a pair of tabs 31 of suitable length, each having a fastener button 32 at one end, are secured to one of the side strips 20 11, and male fastener members cooperating with buttons 32 are secured to the other side strip.

Variations and modifications may be made within the scope of this invention and portions of the improvements may be used without others.

25 Having thus described the invention, what is claimed as new is:

1. A skate scabbard comprising side strips; a pocket separate from said strips but secured to one extreme end thereof so as to extend beyond the same; and a base strip separating said side strips and being of greater length than said side strips so as to project into said pocket.

2. A skate scabbard comprising side strips; a base strip separating said side strips and having a portion projecting beyond one end of said side strips; and a front strip looped about the end of the projecting portion of the base strip and secured at its free ends to one extreme end of said side strips.

3. A skate scabbard comprising a pair of side strips; a base strip of tapered cross-section interposed between one lateral edge of said side strips so as to incline the same toward each other, and having a portion projecting beyond one end of said side strips; and a member of flexible material looped about the end of the projecting portion of said base strip and secured at one lateral side to said base strip and at its free ends to the said end of the side strips so as to 10 form a toe pocket thereon.

4. A skate scabbard comprising a pair of side strips having upper edges; a pocket separate from said side strips but secured to one end thereof so as to extend beyond the same; a base 15 strip separating said side strips and having a portion projecting beyond the end thereof and into said pocket; and contacting portions on said base strip and on at least one of said side strips, so shaped relative to each other as to incline said one of said side strips toward the other of said side strips at the upper edges thereof.

5. A skate scabbard comprising a base strip; a pair of side strips spaced apart by said base strip and secured to opposite sides thereof; an 25 integral looped member having a closed end and having side portions with free ends, said free ends being secured to adjacent side strips at one end of said side strips, and said closed end and said side portions all extending appreciably beyond said end of said side strips; and outer surfaces on said side strips adjacent said end, underlying said side portions and inclined toward each other in the direction of said end to bring said side portions of the looped member closer 30 35 to each other.
